CONVERSION OF HYDROCARBON OILS

Gustav Egloff, Chicago, Ill., assignor to Universal
Oil Products Company, Chicago, Ill., a corpora-
tion of South Dakota

Application March 3, 1931, Serial No. 519,872

1 Claim. (Cl. 196—58)

This invention relates to the treatment of hydrocarbon oils and particularly refers to the conversion of hydrocarbon oils into lighter and more valuable products.

5 Primarily the invention comprises preheating raw oil charging stock for cracking by indirect contact with relatively hot residual oil within a reaction chamber of a cracking system and thence supplying the preheated raw oil to the same 10 cracking system for conversion.

As a feature of the invention the preheated raw oil may be supplied to the heating element of the cracking system at any one or a plurality of points including the inlet to the heating element, the discharge from the heating element as 15 well as intermediate points within the heating element.

Among the benefits which may be derived by preheating the raw oil in the manner provided 20 by the present invention the residual liquid products of conversion are preferably cooled sufficiently to prevent deleterious secondary reactions within the body of residual liquid in the reaction chamber and may thus obviate the excessive formation of coke or carbonaceous material and generally improve the quality of the 25 residual product produced by the system.

In its more specific embodiment the invention 30 may comprise subjecting hydrocarbon oil to conversion conditions in a heating element, introducing the heated products into an enlarged reaction zone where vapors may be separated from residual oil, subjecting the vapors to fractionation, returning the relatively heavy insufficiently 35 converted components of the vapors to the heating element for reconversion, subjecting the relatively light fractionated vapors to condensation and cooling and collecting the resulting products, subjecting raw oil charging stock for the system 40 to indirect contact with the relatively hot residual oil within the reaction chamber and supplying the preheated raw oil either into the inlet to the heating element or into the discharge from the heating element or into one or a plurality of 45 intermediate points in the heating element or in any combination of these manners, as desired.

The attached diagrammatic drawing illustrates 50 one form of apparatus incorporating the principles of the present invention. The following description of the drawing embraces also a description of the process of the invention as it may be practiced in the apparatus illustrated. Raw oil charging stock may be supplied through line 1 and valve 2 to pump 3 from which it may 55 be fed through line 4 and may, if desired, pass

in part through valve 5, in line 4, and through line 6 and valve 7 into fractionator 8. Preferably all or a portion of the raw oil charging stock passes either through line 9 and valve 10 into preheating coil 11 or through valves 5 and 12, in line 4, through preheating coil 13, line 14, valve 15 and line 9 into preheating coil 11. The raw oil, if any, supplied through line 6 and valve 7 to line 8 may be preheated by direct contact with the relatively hot vapors undergoing fractionation in this zone. Preheating coil 13, as here illustrated, may be located in fractionator 8 and the raw oil, if any, fed therethrough may be preheated by indirect contact with the vapors in this zone. It will be understood that preheating coil 13 may or may not be used, as desired, and that other well known means of preheating the raw oil charging stock may be employed instead of or in conjunction with the method illustrated.

Preheating coil 11 may be located within the lower portion of reaction chamber 16 and preferably a portion or all of the raw oil charging stock is supplied thereto, as previously indicated. The raw oil is indirectly contacted in preheating coil 11 with the relatively hot residual liquid within chamber 16 serving to cool the residual oil and being thereby preheated. The preheated raw oil from preheating coil 11 may pass through line 17 and may be subjected to conversion conditions by being fed into the cracking system in one or in any combination of several manners. Preheated raw oil may, for example, pass from line 17 through line 18 and valve 19 into line 20 and thence to heating element 21 or it may pass through line 22 and valve 23 into line 52 which is the discharge line from heating element 21 or preheated raw oil may pass through one or a plurality of lines 24 controlled by valves 25 into any desired intermediate point or points in heating element 21.

Heating element 21 may be located within any suitable form of furnace 26 and the oil supplied thereto may be heated to any desired conversion temperature preferably under a substantial superatmospheric pressure. The heated oil may be discharged through line 52, valve 27 and valve 28 into reaction chamber 16. Separation of vapors and residual oil may be effected in chamber 16. The residual oil may be withdrawn to storage or to further treatment, as desired, through line 29 and valve 30. Vapors from chamber 16 may pass through line 31 and valve 32 to be subjected to fractionation in fractionator 8. Insufficiently converted components of the vapors subjected to fractionation may be condensed in

the fractionating zone and supplied through line 33 and valve 34 to pump 35 which preferably returns this product together with any desired portion of the raw oil charging stock which may have 5 been fed directly into the fractionator, as previously described, through line 20 and valve 36 to heating element 21 for reconversion. Relatively light fractionated vapors of the desired composition may pass from fractionator 8 through line 10 37 and valve 38 to be subjected to condensation and cooling in condenser 39, products from which may pass through line 40 and valve 41 to be collected in receiver 42. Uncondensable gas may be released from receiver 42 through line 43 and 15 valve 44. Distillate may be withdrawn through line 45 and valve 46. A portion of the distillate may, if desired, be withdrawn from receiver 42 through line 47 and valve 48 to pump 49 to be recirculated through line 50 and valve 51 to fractionator 8 to assist fractionation of the vapors in 20 this zone.

Pressures employed within the system may range from subatmospheric to superatmospheric pressures as high as 2000 pounds or more per 25 square inch. Substantially equalized pressure may be employed throughout the system or differential pressures may be utilized between the various elements. Conversion temperatures employed may range from 800 to 1200° F., more or 30 less.

As a specific example of operating conditions which may be employed and results which may be obtained from the operation of the process of the present invention a 22-24° A. P. I. gravity fuel 35 oil is the raw oil charging stock which, after pre-heating by indirect contact with the relatively hot residual oil in the lower portion of the reaction chamber, is introduced in part into the upper portion of the heating element and in part into 40 the discharge from the heating element. The reflux condensate from the fractionator of the system is subjected in the heating element to a maximum temperature of about 975° F. but this

temperature is decreased by the introduction of raw oil and the stream of heated products entering the reaction chamber is at a temperature of about 900° F. The heating element is maintained under a superatmospheric pressure of approximately 250 pounds per square inch and this pressure is substantially equalized throughout the succeeding portions of the system.

This operation may yield approximately 55 percent of motor fuel having an anti-knock value approximately equivalent to a blend of 50 percent benzol and 50 percent Pennsylvania straight-run gasoline. About 10 percent of pressure distillate bottoms and some 28 to 30 percent of marketable fuel oil may also be produced. The remaining 5 to 7 percent is chargeable to gas and a negligible percentage of carbon.

I claim as my invention:

In a cracking process of the character wherein hydrocarbon oil is maintained under cracking conditions of temperature and pressure in an enlarged reaction zone and vapors removed from the reaction zone and subjected to fractionation, the method which comprises preheating a portion of the charging oil for the process by heat exchange with the vapors undergoing fractionation, passing the thus preheated charging oil, in admixture with reflux condensate formed by the fractionation, to a heating zone and heating the same to cracking temperature under pressure 100 while flowing in a restricted stream through the heating zone, discharging the hot oil stream into said reaction zone, passing another portion of the charging oil for the process in indirect heat exchange relation with hot liquid oil constituents in the reaction zone whereby it is pre-heated to higher temperature than the first-mentioned portion of the charging oil, and then combining said other portion of the charging oil with said hot oil stream discharging into the reaction zone.

GUSTAV EGLOFF.
